UNITED STATES PATENT OFFICE

105,523

DESIGN FOR A TEXTILE FABRIC

Jacques Heim, Paris, France

Application July 1, 1937, Serial No. 70,188

Term of patent 3½ years

To all whom it may concern:

Be it known that I, Jacques Heim, a citizen of France, residing at Paris, 15 Avenue Matignon, Department of Seine, have invented a new, original, and ornamental Design for a Textile Fabric, of which the following is a specification, reference being had to the accompanying drawing, forming part thereof, wherein,

The figure is: a plan view of a piece of textile fabric showing my new design.

I claim:

The ornamental design for a textile fabric substantially as shown.

JACQUES HEIM.
